UNITED STATES PATENT OFFICE

FRANK VIENNA, OF LOS ANGELES, CALIFORNIA

INSERT-CONTAINER FOR GARBAGE RECEPTACLES

Application filed June 19, 1930. Serial No. 462,329.

This invention has reference to garbage receptacles and more particularly to an improved insert-container for insertion in and removal from the receptacle to facilitate collection of the garbage.

An object of the invention is to provide an insert container of the above mentioned character which embodies novel features of construction whereby the sides of the insert-container are prevented from being expanded, by the contents thereof, into binding engagement with the surrounding wall of the receptacle, thus facilitating the removal of the filled container without any tearing strain thereon.

15 An additional object is to provide an insert-container having a disinfectant receiving cup or pocket on the inside thereof.

With the above and other objects in view, the invention consists in the novel features of 20 construction and arrangement of parts hereinafter more fully described, with reference to the accompanying drawings, wherein:

Figure 1 is a longitudinal cross sectional view of a garbage receptacle with the invention applied thereto, and

25 Figure 2 is a top plan view of an insert-container.

In the drawings, a garbage receptacle of conventional design is indicated at 1, and, 30 as shown, is provided with the usual flange cover 2. Within the receptacle is adapted to be disposed a removable, flexible, insert-container formed of suitable waterproof material such as oiled paper, and in which is deposited the garbage or other refuse.

The insert container is indicated at 3 and comprises a sack having its upper edge bent outwardly and downwardly to provide a supporting flange 4 which engages over 35 the upper edge of the receptacle and supports the sack within the same. The sack is of a length to extend substantially to the bottom of the receptacle and at the portion 40 adjacent to the supporting flange 4, the sack is of such diameter as to fit snugly against the confining wall of the receptacle.

From the portion 5 downwardly, the sack is of gradually decreasing diameter so that 45 the sides recede from the surrounding wall of the receptacle as the bottom 6 thereof is

approached. By reason of the clearance space 7 thus provided between the adjacent wall of the receptacle and the sack, the sides of the latter will not be expanded or otherwise forced into binding contact with the 55 receptacle wall by the pressure of its contents, and the clearance between the sack and receptacle increases as the sack is lifted out of the same, due to the inclination of the side wall of the sack. Hence, the removal of 60 the garbage contents from the receptacle is accomplished without any tearing strain on the sack. Affixed to the inside of the sack, adjacent its upper end, is a rectangular piece 8 of the same material as the sack which is 65 glued or otherwise secured along its sides and bottom margins to provide an open top pocket or cup for receiving disinfectant.

From the foregoing it will be seen that 70 the invention provides a simple and inexpensive insert-container for garbage receptacles, novel features and practical advantages not found in other similar devices.

Having thus described my invention, what I claim as new is:

An insert container for garbage receptacles comprising a sack of flexible waterproof material having a disinfectant receiving pocket on an inner wall thereof adjacent its upper end, said pocket being formed with 80 a small sheet of flexible waterproof material fastened at its side and bottom edges to the sack with its major portion pressed outwardly away from the wall of sack to which it is connected to form a pocket.

85 In testimony whereof I affix my signature.

FRANK VIENNA.
